UNITED STATES PATENT OFFICE.

JULIUS HIRSCH, OF BROOKLYN, NEW YORK.

DESIGN FOR A SALTCELLAR.

55,271.

Specification for Design.

Patented May 25, 1920.

Application filed February 24, 1920. Serial No. 361,003. Term of patent 3½ years.

To all whom it may concern:

Be it known that I, JULIUS HIRSCH, a citizen of Germany, residing at Brooklyn, Kings county, State of New York, have invented a new, original, and ornamental Design for a Saltcellar, of which the following is a specification, reference being had to the accompanying drawing, forming part hereof, wherein is illustrated a perspective view of a saltcellar embodying my new design.

I claim:

The ornamental design for a saltcellar, as shown.

Signed at New York city, N. Y., this 20 day of February, 1920.

JULIUS HIRSCH

Witnesses:

FELIX WOHLGEMUTH,
MAURICE BLOCK.
